HAND OPERATED TOY

Hans Biller, Nuremberg, Germany

Application April 5, 1935, Serial No. 14,897
In Germany May 16, 1934

4 Claims. (Cl. 46—40)

My invention relates to a hand operated toy consisting of a flat body and representing the figure of a soldier which carries a gun and executes the movements "shoulder arms" and "ground arms" in a true manner. For this purpose the right forearm together with a sheet strip member carrying a gun, a flag or any similar object is moved towards the left arm by actuating a lever device and the object, in this instance a gun is held in the lifted position, while the right forearm returns to its original position. By actuating again the lever device the right forearm swings towards the left arm, at the same time the lifted gun is released and returns together with the right forearm to its original position.

The accompanying drawings illustrate the object of the invention by way of example, in which

Fig. 1 is a front view of the toy showing the position "ground arms" (original position)

Fig. 2 is a front view showing the position "shoulder arms" (highest position of the right forearm)

Fig. 3 is a front view showing the position "shoulder arms" (right forearm in original position)

Fig. 4 is a plan view of the toy.

Figs. 5 and 6 are a front view and a side view respectively of the right forearm,

Figs. 7 and 8 are a front view and a side view respectively of the sheet strip member,

Fig. 9 is a side view of the cam disk,

Figs. 10 and 11 are a front view and a section respectively on line XI—XI of Fig. 10 of the control lever,

Fig. 12 is a section across the left arm on line XII—XII of Fig. 3,

Fig. 13 is a front view of a further form of execution of the toy, and

Fig. 14 is a vertical section on line XIV—XIV of Fig. 13.

According to my invention the right forearm 2 is movably journaled about a fulcrum 3 on the flat toy body 1 and provided with a bracket 4 projecting rearwards. About the said fulcrum 3 is movably located a sheet strip member 5 carrying on its upper edge an extension 6 which projects into the path of movement of the forearm 2. The sheet strip member 5 is provided with a rearwards extending projection 15 and turnably located about the fulcrum 3 between the forearm 2 and the flat toy body 1 (Fig. 4). The sheet strip member 5 is influenced by a spring 7 having the tendency to move said strip member back to its original position as shown in Fig.

1. The gun 8 is turnably connected to the sheet strip member 5 by means of a pin 9, so that the gun 8 can move freely about the pin 9. On the front side of the toy body 1 projecting stop members 10, 11 and 12 are positioned which serve to give the gun an upright position when its abuts against said stop members as shown in Fig. 2. The left arm 13 rocks about an axle 14 and is under the influence of the spring 7 engaging with the one end the arm 13 while the other end engages the projection 15 of the sheet strip member 15. Of the rear side of the toy body 1 a cam disk 17 is turnably mounted about the axle 16, against which the left arm 13 bears by means of a projecting member 18 adapted at the lower end of the arm (Fig. 12). Said projecting member 18 is moved underneath the gun when the left arm is rocked, whereby the gun is kept in lifted position. The cam disk 17 is provided with holes 19, into which an elastic locking tongue 20 stamped out of the toy body 1 engages in such a manner, that the cam disk 17 turns only in the direction as indicated by the arrow (Fig. 1). By turning the cam disk 17 in the indicated direction the cams of the disk 17 actuate the projecting member 18 of the arm 13, whereby the latter leaves the locking position underneath the gun and releases it. Further a control lever 22 is movably mounted at the rear side of the toy body 1 about the axle 16 of the cam disk, said control lever is provided with an elastic catch tongue 23 engaging the holes 19 and operating the cam disk (Figs. 10 and 11). The one arm 24 of the control lever 22 engages the bracket 4 of the right forearm and the opposite arm 25 of the lever 22 is connected to an operating lever 26 rocking about an axle 27. Said operating lever 26 projects with its outer end 28 the rim of the toy body and a spring 21 returns the operating lever to its original position.

Actuating a pressure upon the operating lever 28 the control lever 22 is moved to the position according to Fig. 2, whereby the right forearm 4 swings towards the left arm 13 imparting its motion to the sheet strip member 5 by aid of the extension 6, said strip member carries the gun 8. The toy figure takes the position "shoulder arms" according to Fig. 2 in which the stop members 11 and 12 cause the upright position of the gun 8. Moving the control lever the cam disk 17 is turned by engaging the catch tongue 23 into the holes 19, whereby said cam disk 17 is moved to the next following hole in such a manner, that the projecting member 18 of the left arm 13 leaves the cam disk and by the action of the spring 7 55

the left arm 13 is moved from the position indicated in dotted lines of Fig. 2 to the position according to the full lines of the same figure, whereby the gun is supported by the projecting member 18 at the lower end. Ceasing the pressure upon the operating lever 28 the right forearm 2 is returned to its original position by the action of the spring 21 by means of the control lever 22 while the sheet strip member 5 remains 10 in the position shown in Fig. 3. Moving again the operating lever 28 downwards by pressure, the cam disk 17 is moved by means of the catch tongue 23, so that the right forearm is lifted and the projecting member 18 of the left arm 13 is 15 moved back to the position shown in dotted lines in Fig. 2. So the gun is released and the sheet strip member 5 together with the gun and the right forearm return to the original position by the action of the spring 7 and by the control lever 20 22 respectively, while the stop members 10 and 6 lead the gun to its upright position.

According to Figs. 13 and 14 the hand operated toy is constructed in such a manner, that the flat toy body represents a group of figures, 25 for example three soldiers 1a, 1b and 1c which are positively operated and execute the same movements together. The first figure 1a only carries the cam disk 17 which is turnably mounted about the axle 16 and coacts with the 30 control lever 22a. The other figures 1b and 1c are fitted with control levers 22b and 22c, in this case all the levers are positively connected by a rod 29 having an extension 30 provided with a slot 31, in which the operating lever 26 engages 35 while the outer end 28 projects the rim of the toy body. A spring 32 returns the rod 29 to its original position and also the operating lever 26, 28. The projecting members 18a, 18b and 18c moving underneath the guns 8 are adapted onto a slide member 33 on the rear side of the toy body and 40 project through suitable apertures towards the front of the toy body. Said slide member 33 is suspended on arms 34 and is pressed continually by means of a spring 35 in the direction of the indicated arrow against the cam disk 17. The 45 projecting member 18a of the first figure 1a bears owing to the action of the spring 35 against the cam disk 17, so that all the projecting members 18a, 18b and 18c are operated, when the cam disk is turned and all the guns are held or released respectively.

Actuating a pressure upon the operating lever 28 the control levers 22a, 22b and 22c of every figure are positively moved by means of the connecting rod 29 and all the forearms 2 with the guns are lifted to the position A shown in Fig. 13 by the indicated arrows and the dotted lines. Simultaneously the cam disk 17 of the first figure is moved by aid of the catch tongue 23 adapted 55 on the control lever 22a, whereby the slide member 33 carrying the projecting members 18a, 18b and 18c is moved against the action of the spring 35 towards the direction of the indicated arrow and the lifted guns rest on the projecting members. Ceasing the pressure on the operating lever 60 28 the forearms return to their original position owing to the action of the spring 7, while the sheet strip members 5 together with the guns remain in the lifted position. By a further pressure upon the operating lever 28 the cam disk 17 is turned again, so that by the following cam of the disk the slide member 33 carrying the projecting members 18a, 18b and 18c is moved to

the right, whereby all the projecting members release the guns and the sheet strip members 5 carrying the guns and the forearms 2 are returned together to their original position owing to the action of the spring 32 and the springs 7 respectively.

What I claim is:

1. A hand operated mechanical toy consisting of a flat body and representing a soldier with a movable forearm, comprising in combination a sheet strip member disposed to coact with said forearm, a gun carried by said sheet strip member and adapted to be lifted from the position "ground arms" at the right side to the position "shoulder arms" at the left side, projecting stop members positioned on the front side of said toy body and adapted to give the lowered and lifted gun its upright position, locking means adapted to hold the gun in the lifted position "shoulder arms", a control device actuating said forearm and said sheet strip member, an operating lever coacting with said control device.

2. A hand operated mechanical toy consisting of a flat body and representing a soldier with a movable forearm, comprising in combination a sheet strip member disposed to coact with said forearm, a bracket projecting rearwards and being connected with said forearm, a gun carried by said sheet strip member, projecting stop members positioned on the front side of said toy body, a rocking left arm located movably on said toy body, a spring adapted to influence said left arm, a projecting member adapted on the lower end of said left arm, a cam disk actuating said projecting member, a control lever movably mounted and adapted to engage the bracket of said forearm, a control device actuating said cam disk and an operating lever coacting with said control device.

3. A hand operated mechanical toy consisting of a flat body and representing a group of soldiers with movable forearms, comprising in combination a sheet strip member disposed to coact with each forearm of each figure, a gun carried by said sheet strip member of each figure and adapted to be lifted from the position "ground arms" at the right side to the position "shoulder arms" at the left side, projecting stop members positioned on the front side of each figure, locking means adapted to hold the gun of each figure in the lifted position "shoulder arms", a control device actuating all said forearms and all said sheet strip members, an operating lever coacting with said control device.

4. A hand operated mechanical toy consisting of a flat body and representing a group of soldiers with movable forearms, comprising in combination, a sheet strip member disposed to coact with each forearm of each figure, a gun carried by said sheet strip member of each figure, projecting stop members positioned on the front side of each figure, projecting members adapted to coact with said gun of each figure, a slide member carrying all said projecting members, arms suspending movably said slide member, a cam disk arranged on the end figure and adapted to coact with said slide member, a control lever mounted movably on each figure and adapted to engage said bracket of each figure, a rod connecting all said control levers, a spring influencing said rod and an operating lever coacting with said rod.

HANS BILLER.
